UNITED STATES PATENT OFFICE.

CHARLES E. WILLEY, OF LOUISVILLE, KENTUCKY.

RADIODETECTOR.

Application filed August 28, 1922. Serial No. 584,614.

To all whom it may concern:

Be it known that I, CHARLES E. WILLEY, a citizen of the United States, residing at Louisville, in the county of Jefferson and State of Kentucky, have invented certain new and useful Improvements in Radiodetectors, of which the following is a specification.

This invention relates to wireless receiving apparatus and more particularly to the devices known as crystal detectors.

An object of the invention is to provide an improved construction and arrangement of parts for supporting the detector shaft, whereby such shaft is capable of universal adjustment and whereby it will accurately remain in adjusted position. Another object is to provide an improved means for mounting the crystal.

With the above objects in view, and to improve generally upon the details of construction of such apparatus, my invention consists in the combination and arrangement of parts as hereinafter described and claimed, and shown in the accompanying drawing, forming part of this specification, and in which:

Fig. 1 is a plan view of my improved detector stand, the different positions of the parts being indicated by dotted lines;

Fig. 2 is a side elevation thereof; and

Fig. 3 is a vertical section on an enlarged scale, substantially on the line 3—3 of Fig. 1.

Referring to the drawings in detail, my improved detector stand comprises a suitable base 1, on which are mounted the usual binding posts 2 and 3, which are connected with the detector elements in any suitable way.

Set into the base is a screw 5 secured by a nut 6, preferably received in a recess in the bottom of the base. At its other end, the screw 5 is provided with a relatively large cylindrical head 4 resting on the upper surface of the base, as clearly shown in Fig. 3, and thus constituting a boss or projection. Adapted to fit over this boss 4 is a cylindrical container or holder 7, preferably formed of a short section of metal tubing. The upper end of this container or holder is closed by a plug 8 of soft fusible metal, which is preferably cast in the container so as to completely fill the same for a distance of approximately half its length, as shown in Fig. 3, and in this plug 8 of fusible metal is embedded the crystal 9, which may be of

any suitable character. The crystal, of course, projects above the upper surface of the fusible metal, and the upper edge of the container 7 is preferably beveled off, as indicated at 10. It will be understood that the lower end of the holder or container 7 is adapted to be removably mounted on the boss 4 with a snug fit, this boss serving to retain the holder in position on the base and also constituting the electrical terminal which is connected to the binding post 3, as indicated in Fig. 1.

A second screw 11 passes up through the base 1, with its head received in a recess on the under side thereof, as shown in Fig. 3, and is secured in position by means of a lock nut 13. The shank 12 of the screw extends a considerable distance above the lock nut and is screw threaded throughout its length, as shown.

Engaging this screw threaded shank or stud is a hollow nut or bearing member 14, and extending transversely through the upper end of this nut or bearing member is a shaft 15. This shaft is loosely mounted in the bearing member 14 so as to be capable of free rotary and sliding movement, relative thereto. On one end of the shaft 15 is mounted a knurled thumb nut 16 or the like, by means of which the shaft may be adjusted, and to the other end of the shaft is secured, as by means of a pin 18, one end of a contact wire or cat whisker 17. The free end of this cat whisker is preferably formed into a short spiral 19, for the sake of resilience, and is positioned so as to engage the upper surface of the crystal 9.

It will be seen that the contact wire 17 extends generally in a direction at substantial right angles to the shaft 15, and thus by rotating this shaft on its own axis, the free end of the cat whisker may be raised or lowered, as indicated in dotted lines in Fig. 2. By sliding the shaft 15 through its bearing in the nut 14, the position of the cat whisker or contact wire transversely of the base may be varied, and by swinging the shaft in a horizontal plane, as indicated in dotted lines in Fig. 1, it may be angularly displaced relative to the base and crystal holder, such swinging movement being possible by reason of the turning of the nut 15 on the screw threaded stud 12. Thus, it will be seen that the contact wire or cat whisker is capable of three different kinds of movements; in other words, it is mounted

for universal adjustment, so that its free end may be manipulated as desired to secure the most effective cooperation with the crystal 9.

5. In order to yieldingly hold the parts against accidental displacement, so that the adjustment of the contact wire may be accurately maintained, I provide a spring 20. As shown, this is a short helical spring of 10 the compression type and is enclosed within the hollow nut 14, with one end bearing against the end of the stud 12 and the other end bearing against the side of the shaft 15. It will be seen that the pressure of this 15 spring not only frictionally holds the shaft itself against accidental displacement, but also produces sufficient friction between the nut 14 and threaded stud 12 to hold the latter against angular displacement relative to 20 the stud. Thus, a single spring serves to maintain all three adjustments. Moreover, by completely rotating the nut 14 on the threaded stud 12, the pressure exerted by 25 said spring may be increased or diminished 30 as desired. Thus, by this simple expedient, means are provided for adjusting the degree of frictional resistances which the spring produces, and this adjusting is accomplished by the same means which permits the turning or swiveling of the detector shaft about the stud 12.

It will thus be seen that I have provided an exceptionally simple and at the same time, very effective construction of detector stand, whereby all desired adjustments may be quickly made and permanently retained, and it is thought that the many advantages of my improved construction will be readily appreciated without further discussion.

40. What I claim is:

1. A detector stand comprising a rigid bearing member, a shaft mounted for free rotary and sliding movement in said member, a contact wire carried by said shaft, and a separate compression spring independent of said member bearing against the side of said shaft to frictionally hold the same in any position to which it may be adjusted.

50. 2. A detector stand comprising a hollow-bearing member, a shaft extending transversely through said member and capable of both sliding and rotary adjustment therein, a contact wire carried by said shaft, and a spring independent of but located within said hollow member and bearing against the side of said shaft to frictionally retain the same in adjusted position.

3. A detector stand comprising a hollow bearing member, a stud on which said member is swiveled, a shaft extending through said member in a direction transverse to the axis thereof, and capable of both sliding and rotary adjustment therein, a contact wire carried by said shaft, and a spring enclosed within said hollow member and bearing at one end on said stud and at the other end against said shaft, whereby the said shaft is frictionally held against accidental displacement in all directions. 70

4. A detector stand comprising a hollow bearing member, a stud on which said member is swiveled, a shaft extending through said member in a direction transverse to the axis thereof, and capable of both sliding and rotary adjustment therein, a contact wire carried by said shaft, a spring enclosed within said hollow member and bearing at one end on said stud and at the other end against said shaft, whereby the said shaft is frictionally held against accidental displacement in all directions, and means for adjusting the pressure exerted by said spring. 75

5. A detector stand comprising a fixed, screw threaded stud, a nut engaging said stud, a shaft extending transversely through said nut and capable of both rotary and sliding adjustment therein, a contact wire carried by said shaft, and a spring within said nut interposed between the end of said screw threaded stud and said shaft, whereby both the shaft and nut are frictionally held in adjusted position. 85

6. In a detector stand, the combination with means for adjustably supporting a cat-whisker, of a crystal holder comprising a cylindrical container, a plug of soft metal permanently mounted in and filling one end of the container, and a crystal embedded in said soft metal, the other end of said cylindrical container being free and open, and constituting a socket. 95

7. In a detector stand, the combination with means for adjustably supporting a cat-whisker, of a crystal holder comprising a cylindrical container, open at both ends, a plug of soft metal mounted in and filling one end of the container, a crystal embedded in said soft metal, and a fixed boss over which the other end of said container removably fits. 105

In testimony whereof I affix my signature.

CHARLES E. WILLEY.
